UNITED STATES PATENT OFFICE.

ARTHUR McDougall DUCKHAM, OF LONDON, ENGLAND.

PROCESS FOR THE FIXATION OF NITROGEN.

Application filed September 25, 1922. Serial No. 590,518.

To all whom it may concern:

Be it known that I, ARTHUR McDougall DUCKHAM, a subject of the King of Great Britain, residing in London, England, have 5 invented a certain new and useful Improved Process for the Fixation of Nitrogen, of which the following is a specification.

This invention relates to a process for the fixation of nitrogen by means of a heated 10 mixture of barium carbonate or oxide, with carbon. The processes hitherto proposed for this purpose which have been conducted in an externally heated retort, have not been successful commercially and this lack of success when working with a vertical retort is 15 partly due to the facts that the heated material attacks the highly heated walls of the retort or the like in which it is heated and that the material is apt to cake and attach 20 itself to the walls of the retort and so in time to prevent the passage of the material through the retort. The working with a horizontal retort has been unsuccessful because of the difficulties attendant to the 25 withdrawal of the material in a highly heated state.

According to this invention the portions 30 of the retort, muffle or oven, with which the material comes into contact, are not directly heated, and preferably the material is so arranged that it protects the portions of the retort with which it is in contact from the heat.

This result is most easily attained by 35 spreading the material in a thin layer on the bottom of a muffle furnace and applying heat only to the roof of the furnace.

In order that the process may be continuous we preferably form the bottom of the 40 muffle as a conveyor so that the material on the conveyor nowhere touches the walls of the muffle and is gradually heated and then cooled in its passage through the muffle.

A furnace suitable for carrying out this 45 process is that forming the subject-matter of U. S. Patent No. 1,436,582, granted to me November 21, 1922. This is shown in the accompanying drawings, wherein Figs. 1 and 2 are developed longitudinal vertical 50 sections through the furnace. Fig. 3 is a cross-section on the line 3-3, Fig. 1, Figs. 4, 5, 6, 7 and 8 are cross-sections, respectively, on the lines 4-4, 5-5, 6-6, 7-7, and 8-8, Fig. 2, and Fig. 9 is a sectional plan view 55 upon a reduced scale.

Referring to Fig. 9, the furnace is con-

structed of concentric walls *a* at the centre of which is a chimney *b* connected with the furnace through a flue *c* shown in dotted lines. The walls are carried on girders *d* supported on piers *y* (Figs. 1, 2 and 3) and the space between the inner of these girders is closed by plates *d*¹ (Figs. 5 and 8). At equiangular distances apart the plates carry depending pockets *d*² (Figs. 3 and 4) which 60 contain bearings for rollers *e*. On the latter are supported the flanges of an annular girder *f* carrying an annular platform *g* constructed of hollow brickwork filled with concrete *g*¹, and the upper surface of the 65 platform is formed as a shallow trough having its bottom *l* of convex cross section of radius similar to that of the roof *h* spanning the space between the walls *a* and forming with these and the plates *d*¹, the muffle 70 chamber.

The girder *f* carries a rack *f*¹ which is in gear with a suitably driven pinion *f*² (Fig. 7) so that the platform is continuously rotated.

The mixture of barium carbonate and carbon is fed continuously into the trough of the platform through a gas-tight feeding device *g*³ and a chute *g*¹ (Fig. 4) at a part of the muffle which is not heated by the flues 80 presently to be described. The direction of travel being that shown by the arrow in Figs. 1 and 2, the forward side of the chute *g*¹ carries an adjustable plate *g*² (Fig. 2) which serves to determine the depth of the 85 layer of material in the trough.

The roof *h* of the muffle is heated by combustion of gases in the heating flue *z*, the draught being in the direction opposite that of the platform, namely from the air inlet *i* 90 to the waste gas outlet *k* (Fig. 5) and chimney flue *c*, the former being directly in front of the charging chute *g*¹.

The gas enters the flue *z* through ports *m*, more or less diametrically opposite the 100 charging chute *g*¹ and considerably in advance of the air inlets *i* (Fig. 9); thus the portion of the flue between these points serves for preheating the air and at the same time cooling the material.

Immediately behind the charging chute *g*¹ is the device for removing the material. This consists of a casing *n* containing a bucket conveyor *o* suitably driven from the shaft of pinion *f*², for instance, as indicated 110 in Fig. 7. The front side of the casing carries a scraper plate *p*¹ which is vertically

adjustable so that it can be placed in position to remove the upper portion of the layer of the material contained in the trough and causes it to be picked up by the buckets of 5 the conveyor and discharged into a horizontal air-tight worm conveyor *p* (Fig. 7) from which it is discharged by an air-tight rotary device *q*.

For supplying the gas to the muffle chamber there is provided a flue *r* above the heating flue *s* to which the gas is supplied through port *s*. From here it travels in direction opposite to that of the heating gas to short vertical flues *t* which connect the 10 flue *r* with the interior of the muffle (Fig. 15 3). Passing through these into the muffle, the gas reverses its direction and travels to the outlet *u* where it leaves the muffle by 20 passages *v*.

20 *w* is a heat insulating air-space.

At the part of the furnace where the material is charged and discharged there are 25 preferably substituted for the roof of the muffle, removable plates *x* which permit of 25 inspection and repair of the surface of the platform.

Having thus described the nature of the said invention and the best means I know of carrying the same into practical effect, I 30 claim:—

1. A process for the fixation of nitrogen by means of a mixture of carbon and a barium oxide yielding substance, which process consists in causing a layer of the 35 mixture to travel in an atmosphere of nitrogen beneath an impervious partition heated to a high temperature, the speed of travel being such that while the upper part of the

layer is heated by radiation to the temperature at which reaction occurs the lower part 40 remains at a temperature below this.

2. A process for the fixation of nitrogen by means of a mixture of carbon and a barium oxide yielding substance, which process consists in charging the mixture in the form of 45 a layer on to the annular travelling hearth of a muffle containing nitrogen, heating externally the roof alone of the muffle, removing the upper layer of the material at each revolution of the hearth and substituting for 50 it fresh mixture.

3. A process for the fixation of nitrogen by means of a mixture of carbon and barium oxide, which process consists in causing a 55 layer of the mixture to travel in an atmosphere of nitrogen beneath an impervious partition heated to a high temperature, the speed of travel being such that while the upper part of the layer is heated by radiation to the temperature at which reaction 60 occurs the lower part remains at a temperature below this.

4. A process for the fixation of nitrogen by means of a mixture of carbon and barium oxide, which process consists in charging 65 the mixture in the form of a layer on to the annular travelling hearth of a muffle containing nitrogen, heating externally the roof alone of the muffle, removing the upper layer of the material at each revolution of 70 the hearth and substituting for it fresh mixture.

In testimony whereof, I have signed my name to this specification.

ARTHUR McDougall DUCKHAM.
